UNITED STATES PATENT OFFICE.

WARREN H. VREELAND, OF SENECA FALLS, NEW YORK.

CARPENTER'S GAGE.

SPECIFICATION forming part of Letters Patent No. 788,802, dated May 2, 1905.

Application filed June 11, 1904. Serial No. 212,129.

To all whom it may concern:

Be it known that I, WARREN H. VREELAND, a citizen of the United States, residing at Seneca Falls, in the county of Seneca, in the State of New York, have invented new and useful Improvements in Carpenters' Gages, of which the following is a specification.

This invention relates to gages for laying out and marking the mortises for butt-hinges and for analogous purposes.

The object of the invention is to provide a desirable adjustable gage of simple and inexpensive construction which can be readily set for or marking mortises of different lengths, widths, and depths.

In the accompanying drawings, Figure 1 is an elevation of a gage embodying the invention, showing the same in operative position against a part, such as a door or door-jamb, for marking the hinge-mortise. Fig. 2 is an end elevation thereof. Fig. 3 is a rear elevation of the gage. Fig. 4 is a longitudinal section in line 4-4, Fig. 1. Fig. 5 is a fragmentary section, on an enlarged scale, in line 5-5, Fig. 1. Fig. 6 is a section in line 6-6, Fig. 5.

Like letters of reference refer to like parts in the several figures.

The gage comprises two parallel arms A and a connecting body portion or plate B, to which the arms are adjustably connected to be moved and secured nearer to or farther from each other, as required. The outer edges of the arms are parallel with each other and at right angles to the outer longitudinal edge of the connecting-plate. The latter is a rectangular plate or piece provided in its rear or under side with a longitudinal guide groove or channel b, into which project and slide longitudinal guide-ribs b' on the front or top faces of the arms, which latter are also preferably provided with longitudinal guide-shoulders b² on their front or top faces, which slidably bear against the inner longitudinal edge of the connecting-plate. The end pieces are thus held in exact parallelism with the connecting-plate in their different adjustments.

C represents clamping-screws, which work in holes in the arms and extend through longitudinal slots c in the connecting-plate and are provided with milled heads or finger-

pieces, which bear against the connecting-plate to secure the arms in adjusted positions. The arms can be guided and secured by other means. They are provided, preferably on their front or upper faces, with 55 graduations d, which coöperate with the opposite ends of the connecting-plate to indicate the length of the gage or distance between the outer edges of the adjustable arms.

E' represent adjustable bearing-blocks 60 which are located on the rear or under sides of and project out from the adjustable-arms to bear against the edge of the door, door-jamb, or other part with which the gage is to be used and which are adjustable length- 65 wise of the arms of the gage. The bearing-blocks have screw-threaded stems extending through guide-slots e in the arms of the gage to which they are clamped in adjusted positions by clamp or thumb nuts F, screwed on 70 said stems and adapted to bear against the front or top faces of the gage-arms. The stops can be moved in the slots of the arms and secured at the desired distance from the outer longitudinal edge of the gage, and the 75 arms are provided on their under or rear faces with graduations f to enable the stops to be set for a mortise of known width without the use of a separate gage or rule. The bearing-faces of the stops are preferably con- 80 vexed or rounded so that they will slide smoothly on the work.

The gage is provided with an adjustable marking device G, which is preferably carried by one of the bearing-blocks—for instance, 85 the block E'—for indicating the depth of the mortise. This device consists of a screw-threaded shank which extends through a longitudinal hole in the stem e' of the bearing-block E' and a marking-point g, which projects out laterally through a slot g' in the bearing-block. (See Fig. 5.) The end of the shank of the marking device projects out beyond the end of the stem of the bearing-block and is provided with an adjusting-nut 90 h, which bears against the end of the stem of the bearing-block. When this adjusting-nut is loosened, the marking device can be moved lengthwise of itself or transversely of the arm until the nut engages the end of the stem of 95 100

the bearing-block, and then by turning the nut the marking device can be drawn in the opposite direction to properly position its marking-point. For securely holding the marking device in the position to which it is adjusted the end of the stem e' of the bearing-block is split, as at k , Fig. 6, and is tapered and externally threaded, and a clamping-nut K is screwed on this tapered threaded end of the stem. By tightening up the clamping-nut the split end of the stem is contracted about the shank of the marking device, so as to grip and securely hold the latter. This construction is desirable, as it enables the adjustment of either the bearing-block or the marking device without disturbing the adjustment of the other part. Other means could be employed, however, to adjustably secure the bearing-block and marking device.

20 The gage is used in the following manner: The end arms A are adjusted toward or from each other to lengthen or shorten the gage to correspond exactly with the necessary length of the mortise to be cut, the edge bearing-blocks E E' are adjusted lengthwise of the arms of the gage to position their bearing-faces from the outer longitudinal edge of the gage a distance equal to the width of the mortise, and the marking-point g is adjusted

25 toward or from the rear or under face of the gage-arm a distance equal to the desired depth of the mortise. The gage is then placed on the face of the door, door-jamb, or other part to be cut, with the bearing-blocks

30 against the edge of such part, as shown in Figs. 1 and 2, and lines are drawn along the longitudinal and end edges of the gage, after which the gage is moved along the edge of the door or jamb, so that the marking-point

35 makes a scratch or mark indicating the depth of the mortise. As the marking-point is directly opposite the slot in the gage-arm on which it is mounted, the mark made by the point will terminate at the marks on the face

40 of the door or jamb which indicate the ends of the mortise, if the movement of the gage is arrested when such end mark appears beneath the slot in the arm of the gage, and it is not necessary to unduly mar the work in

45 50 the use of the gage. The gage can be quickly and easily set to mark mortises of different dimensions and is a very desirable device for rapidly marking two or more mortises of the same dimensions.

I claim as my invention—

1. The combination of a plate, an arm adjustably secured to said plate to be adjusted lengthwise of the latter, a bearing-block adjustable lengthwise of said arm, and a marking device adjustable transversely toward and from the face of said arm, substantially as set forth.

2. The combination of a plate, arms extending at right angles to and adjustably secured to said plate to be adjusted toward and from each other, bearing-blocks adjustable lengthwise on said arms, and a marking device which is adjustable lengthwise of one of said arms and also transversely toward and from the face of said arm, substantially as set forth.

3. The combination of a plate, an arm projecting from and adjustable lengthwise of said plate, a bearing-block adjustable on said arm toward and from said plate, and a marking device carried by said bearing-block and adjustable transversely of the direction of adjustment of the block and having a marking portion which extends in a direction substantially parallel with the direction of adjustment of said bearing-block, substantially as set forth.

4. The combination of a plate, an arm projecting from and adjustable lengthwise of said plate, a bearing-block adjustable on said arm toward and from said plate in a plane parallel with the plane of said plate, and a marking device carried by said bearing-block and adjustable transversely of the plane of said plate, and having a marking portion which extends in a direction substantially parallel with the plane of said plate, substantially as set forth.

5. The combination of a plate, a bearing-block movable relative to said plate, means for securing said block in adjusted positions, a marking device carried by said block and movable transversely of the direction of movement of the block, a nut for adjusting the marking device, and a nut for securing the latter in adjusted positions, substantially as set forth.

Witness my hand this 6th day of June, 1904:

WARREN H. VREELAND.
